(57) **CLAIM**

The ornamental design for a multidetector, as shown and described.

DESCRIPTION

FIG. 1 is a left, front perspective view of a first embodiment of a multidetector according to my design, the right, front perspective view being mirror symmetrical;

FIG. 2 is a left side view thereof, the right side view being mirror symmetrical;

FIG. 3 is a top view thereof;

FIG. 4 is a bottom view thereof;

FIG. 5 is a front view thereof; and

FIG. 6 is a rear view thereof.

FIG. 7 is a left, front perspective view of a second embodiment of the multidetector according to my design, the right, front perspective view being mirror symmetrical;

FIG. 8 is a left side view thereof, the right side view being mirror symmetrical;

FIG. 9 is a top view thereof;

FIG. 10 is a bottom view thereof;

FIG. 11 is a front view thereof; and

FIG. 12 is a rear view thereof.

FIG. 13 is a left, front perspective view of a third embodiment of the multidetector according to my design, the right, front perspective view being mirror symmetrical;

FIG. 14 is a left side view thereof, the right side view being mirror symmetrical;

FIG. 15 is a top view thereof;

FIG. 16 is a bottom view thereof;

FIG. 17 is a front view thereof; and

FIG. 18 is a rear view thereof.

FIG. 19 is a left, front perspective view of a fourth embodiment of the multidetector according to my design, the right, front perspective view being mirror symmetrical;

FIG. 20 is a left side view thereof, the right side view being mirror symmetrical;

FIG. 21 is a top view thereof;

FIG. 22 is a bottom view thereof;

FIG. 23 is a front view thereof; and

FIG. 24 is a rear view thereof.

FIG. 25 is a left, front perspective view of a fifth embodiment of the multidetector according to my design, the right, front perspective view being mirror symmetrical;

FIG. 26 is a left side view thereof, the right side view being mirror symmetrical;

FIG. 27 is a top view thereof;

FIG. 28 is a bottom view thereof;

FIG. 29 is a front view thereof; and

FIG. 30 is a rear view thereof.

FIG. 31 is a left, front perspective view of a sixth embodiment of the multidetector according to my design, the right, front perspective view being mirror symmetrical;

FIG. 32 is a left side view thereof, the right side view being mirror symmetrical;

FIG. 33 is a top view thereof;

FIG. 34 is a bottom view thereof;

FIG. 35 is a front view thereof; and

FIG. 36 is a rear view thereof.

FIG. 37 is a left, front perspective view of a seventh embodiment of the multidetector according to my design, the right, front perspective view being mirror symmetrical;

FIG. 38 is a left side view thereof, the right side view being mirror symmetrical;

FIG. 39 is a top view thereof;

FIG. 40 is a bottom view thereof;

FIG. 41 is a front view thereof; and

FIG. 42 is a rear view thereof.

FIG. 43 is a left, front perspective view of an eighth embodiment of the multidetector according to my design, the right, front perspective view being mirror symmetrical;

FIG. 44 is a left side view thereof, the right side view being mirror symmetrical;

FIG. 45 is a top view thereof;

FIG. 46 is a bottom view thereof;

FIG. 47 is a front view thereof; and

FIG. 48 is a rear view thereof.

FIG. 49 is a left, front perspective view of a ninth embodiment of the multidetector according to my design, the right, front perspective view being mirror symmetrical;

FIG. 50 is a left side view thereof, the right side view being mirror symmetrical;

FIG. 51 is a top view thereof;

FIG. 52 is a bottom view thereof;

FIG. 53 is a front view thereof; and

FIG. 54 is a rear view thereof.

FIG. 55 is a left, front perspective view of a tenth embodiment of the multidetector according to my design, the right, front perspective view being mirror symmetrical;

FIG. 56 is a left side view thereof, the right side view being mirror symmetrical;

FIG. 57 is a top view thereof;

FIG. 58 is a bottom view thereof;

FIG. 59 is a front view thereof; and

FIG. 60 is a rear view thereof.

FIG. 61 is a left, front perspective view of an eleventh embodiment of the multidetector according to my design, the right, front perspective view being mirror symmetrical;

FIG. 62 is a left side view thereof, the right side view being mirror symmetrical;

FIG. 63 is a top view thereof;

FIG. 64 is a bottom view thereof;

FIG. 65 is a front view thereof; and

FIG. 66 is a rear view thereof.

FIG. 67 is a left, front perspective view of a twelfth embodiment of the multidetector according to my design, the right, front perspective view being mirror symmetrical;

FIG. 68 is a left side view thereof, the right side view being mirror symmetrical;

FIG. 69 is a top view thereof;

FIG. 70 is a bottom view thereof;

FIG. 71 is a front view thereof; and,

FIG. 72 is a rear view thereof.

The broken lines are for illustrative purposes only and form no part of the claimed design.
